LAMP

Irmi Ann Gross, New York, N. Y.

Application February 18, 1953, Serial No. 23,677

Term of patent 7 years

(Cl. D48—20)

To all whom it may concern:

Be it known that I, Irmi Ann Gross, a citizen of the United States of America, residing in New York city, county of New York, and State of New York, have invented a new, original, and ornamental Design for a Lamp, of which the following is a specification, reference being had to the accompanying drawing, forming part thereof, wherein,

The opposite side of the piano member of the lamp base, not shown, is devoid of ornamentation, and the opposite side of the figurine, not shown, is identical in appearance to the side shown in Figure 1.

I claim:

The ornamental design for a lamp, substantially as shown and described.

IRMI ANN GROSS.
